SECURING DEVICE

George T. Jacocks, Larchmont, N. Y., assignor to
 The Lummus Company, New York, N. Y., a
 corporation of Delaware

Application February 17, 1939, Serial No. 256,935

5 Claims. (Cl. 257—225)

This invention relates to securing devices for detachably securing plates to vessels and more particularly, to floating head cover sealing devices for tubular type heat exchangers having a tube bundle within a shell.

In heat exchanger construction of the typical shell and tube type, an internal cover is secured to a floating or movable tube sheet to transfer the fluid within the tubes from one part of the tubes to another part of the tubes. This cover must be of minimum size in order to keep down the external size of the shell, flanges, etc., and it is normally arranged so that the cover can be removed from one end of the heat exchanger shell, while the tube bundle and floating tube sheet are removed from the other end of the shell. While my invention is of particular importance in securing the cover to the floating tube sheet in such relation, it will also be obvious 40 that it may be used for any similar purpose.

The principal object of my present invention is to provide an improved pressure vessel construction having a removable cover member detachably secured to a plate, such cover member being held sealed irrespective of temperature changes and pressure conditions, and which is readily detached when desired.

Another and more specific object of my invention is to provide a holding clamp mechanism in a heat exchanger for detachably holding a cover to a floating tube sheet with a minimum increase in diameter over the maximum tube diameter and in such positive manner that there is no tendency of the cover to be displaced from the tube sheet.

Another object of the invention is to provide an improved seal for a floating head cover of a heat exchanger so that the cover may be sealed in pressure tight relation to the under side of a floating tube sheet with the seal on top of the plate, such seal including split clamps and a solid securing ring which may be entirely removed from the plate, the clamp members having a minimum thickness, maximum strength, 45 and being simple in construction and being firmly held by the solid ring.

Further objects and advantages of my invention will appear from the following disclosure of a preferred form of embodiment thereof taken 50 in connection with the attached drawing, in which:

Figure 1 is a partial vertical section, as on the line 1—1 of Figure 2, of a heat exchanger embodying a preferred form of the invention; and

Figure 2 is a top plan view, partially broken

away, of the top of the floating tube sheet cover.

My invention, although applicable to any type of sealing device which must be clamped to a plate or shell or member having an opening therein in such a manner that the cover and clamp can be removed from one side of the plate or one end of the shell, is of particular importance in securing the cover to the floating tube sheet of a heat exchanger. For this reason, it will be described in such connection, although 10 no limitation is intended thereby.

The heat exchanger shell 10 normally has a tube bundle 35 anchored at the channel end (not shown) and in order to provide for the necessary expansion, the floating tube sheet 36, to which the other ends of the tubes are secured, is completely movable within the shell cover 18. Circulation of fluid from one part of the tube bundle 35 to the other is accomplished by a floating tube sheet cover 40 and this is sealed by gasket 20 44 to the edge of the tube sheet 36.

Under ordinary circumstances, it is occasionally necessary to remove the entire bundle from the shell of the heat exchanger, which is accomplished by removing the tube bundle from the 25 fixed or opposite end of the heat exchanger. It is therefore necessary that the floating tube sheet 36 be of smaller diameter than any other part of the shell through which it must pass. It is of course, also essential that the floating tube sheet 30 cover 40 be adequately secured to the floating tube sheet 36, and without an excessive size of shell cover 18.

In accordance with my invention, I provide 35 sectional C-clamp members 38 which are conveniently semi-cylindrical members forming a ring split on the major diameter as shown in Figure 2. This C-clamp when in place, not only under-lies the floating tube sheet 36, and has portion 38a engaging the tube sheet, but the C- 40 clamp projects substantially above the tube sheet cover 40 and over-lies the cover as well as the bull ring 41 as shown at 38b.

The underlying and overlying portions 38a and 38b are preferably laterally inwardly projecting 45 angular gripping edges which grip the tube sheet 36 and bull ring 41.

The upper and lower edges of the C-clamp 38 are drawn into the gripping position by the bolts 42 which are screw threaded therein and engage 50 the top of the cover 40. The more the reaction longitudinally due to the outward movement of the bull ring, the greater the gripping tendency of the C-clamp members on the tube sheet and bull ring. Both the tube sheet 36 and the bull 55

ring 41 have the cooperating peripheral channels 36a and 41a for this purpose.

The angle of inclination of the grooves 36a and 41a may be in the neighborhood of 15° which 5 will prevent the C-clamp sections 38 from moving away from the secured parts. It is of course obvious, however, that right angle channels and tongues could be substituted as far as holding reaction is concerned, but there would not be 10 any increase in tightness of the C-clamp members laterally of the tube sheet. Such construction is an alternative, but not as satisfactory.

The construction is far superior to constructions heretofore used in that there is a continuous 15 contact between the C-clamp members and the tube sheet and bull ring which extends through substantially 360°. This exists both at the top and at the bottom and the C-clamp members can not come loose. Longitudinal clearance over the 20 shell flange 10a may also be reduced to a minimum as the slight taper of the engaging parts is such that backing off the bolts 42 will quickly free the clamp sections. It is also possible to effectively control the thickness of the parts for 25 the necessary strength. The machining of the C-clamp members is extremely simple, parts being preferably made reversible. The bull ring has the necessary metal for screw threading and excessive top flanges on the clamp members are 30 unnecessary.

This construction has another important advantage over heretofore proposed arrangements inasmuch as it is possible to reduce the diameter of shell 10 to a minimum as the clearance can 35 be relatively close. The walls of the C-clamp are in tension, and all of the metal is effective. No extra thickness is required for bolts and this would reduce the shell diameter several inches on a 24" diameter high pressure unit. The flange 40 diameter is also reduced to the same extent.

The simplicity, superior strength, reduced size and low cost of the bull ring and C-clamp members commends its use both on internal as well as external joints. It is especially useful on 45 internal joints, however, as it is not affected by heat or pressure or time as the sealing force is directly reacted by balancing forces. Where inspection is difficult, its use is most beneficial.

While I have shown and described a preferred 50 form of embodiment of the invention, I am aware that other modifications may be made thereto and I therefore desire a broad interpretation thereof within the scope and spirit of the description herein and of the claims appended herein- 55 after.

I claim:

1. In a heat exchanger of the class described having a shell, a tube bundle therein, a tube sheet for one end of the tube bundle sufficiently smaller than said shell to be easily removable there- 60 through, and a cover for said tube sheet having a rim engaging the outer face of the tube sheet, the combination of a sectional ring in clamping en-

gagement with said tube sheet, removable means engaging said sectional ring and tending to hold it together, and adjustable members extending between said cover and said removable means and exerting a force therebetween for clamping said 5 cover and tube sheet together.

2. In a heat exchanger of the class described having a shell, a tube bundle therein, a tube sheet for one end of the tube bundle sufficiently smaller than said shell to be easily removable there- 10 through and a cover for said tube sheet having a rim engaging the outer face of the tube sheet, the combination of a sectional ring surrounding said cover and in clamping engagement with said tube sheet, a continuous ring engaging said sec- 15 tional ring to prevent canting of said sectional ring when said cover and tube sheet are clamped together, and means for clamping said cover and tube sheet together.

3. In a heat exchanger having a shell, a tube 20 bundle therein, a tube sheet for one end of the tube bundle, and a cover for said tube sheet having a rim engaging the outer face of the tube sheet, the combination of a clamping element of separate channel cross-section portions encircling 25 the tube sheet and cover, the flanges of the element extending radially inwardly to overlap the opposite faces of the tube sheet and cover for locking them together, and a continuous ring within the channel of the clamping element hav- 30 ing means interlocking with the flanges of the clamping element to hold said portions inwardly.

4. In a heat exchanger having a shell, a tube 35 bundle therein, a tube sheet for one end of the tube bundle, and a cover for said tube sheet having a rim engaging the outer face of the tube sheet, the combination of a plurality of thin-walled segments embracing the peripheries of the tube sheet and cover rim for clamping them together, said segments jointly forming a complete ring, said segments having inwardly projecting gripping portions, continuous ring means 40 engaging part of said gripping portions, and adjustable members cooperating with said ring means for forcing another part of said gripping 45 portions into engagement with the tube sheet.

5. In a pressure vessel of the class described, a member having an opening therein, a cover for said member and means to secure said cover to said member, said means including partially 50 cylindrical C-shaped clamp devices, said devices being movable laterally to a position to engage under said member and over said cover, and means to draw said clamp devices laterally inward toward said cover and member, said means 55 including a ring, adjustable elements in said ring engaging the cover, and laterally inwardly projecting grooves on the inner surface of the member and the outer surface of the ring, said clamp devices having inwardly extending gripping edges 60 engaging in said grooves.

GEORGE T. JACOCKS.
